UNITED STATES PATENT OFFICE.

OLIVER PERRY ANDERSON, OF NASHVILLE, TENNESSEE.

TYPE-BAR.

1,189,522.

Specification of Letters Patent.

Patented July 4, 1916.

Application filed September 21, 1915. Serial No. 51,750.

To all whom it may concern:

Be it known that I, OLIVER PERRY ANDERSON, a citizen of the United States, residing at Nashville, in the county of Davidson and 5 State of Tennessee, have invented certain new and useful Improvements in Type-Bars; and I do hereby declare the following to be a full, clear, and exact description of the invention, such as will enable others skilled in 10 the art to which it appertains to make and use the same.

This invention relates to type bars and is more particularly adapted for typewriting machines.

15 One of the objects of this invention is the production of a type bar provided with attachable and detachable means whereby the character of the type may be readily changed, or in case of damage to the type 20 the same may be readily replaced.

Another object of this invention is the provision of means for efficiently retaining and locking the type upon the type bar.

Other objects and advantages of this invention will be hereinafter more clearly set forth in the specification, defined in the 25 claims, and illustrated in the accompanying drawings, in which,

Figure 1 is a side view of the device. 30 Fig. 2 is an end view of the device shown in Fig. 1. Fig. 3 is a side view, partly in section, showing one means for mounting the type upon the type bar. Fig. 4 is a side view, partly in section, showing another 35 means for mounting the type upon the type bar. Fig. 5 is an end view of the device shown in Fig. 4.

Referring to Figs. 1, 2, and 3 of the drawings, 1 denotes the type bar, provided with 0 the aperture 2 adjacent one of its ends, one end of the aperture being formed with the countersink 3. Mounted upon the type bar 1 is the type block 4, formed with the shank 5, provided with the reduced end or stem 6 5 and the shoulder 7, the stem 6 passing through the aperture 2 of the bar 1 with the shoulder 7 bearing against one face of the type bar 1, and the end of the stem 6 formed type bar 1, and the end of the stem 6 formed with the head 8 within the countersink 3 of 50 the aperture 2, thus securing the type block 4 upon the type bar 1. The type bar 1, the shank 5, and the face of the type block 4 are substantially the same width, but the type block 4 is elongated in the longitudinal direction of the type bar 1. The type block 4

is provided with the flat face 9, the downwardly and inwardly inclined side wall 10, and the straight wall 11 formed with the inwardly directed undercut portion 12. The type block 4 is also provided in its face 9 60 with the recess 13 as shown in Fig. 3. For supporting the type upon the type block 4, a metal support, preferably formed of a flat plate of spring brass, is provided. This support is bent to provide the base plate 14 65 upon which is secured the type 15 and 16, which type may be the small letters and capital letters. The plate or support for the type is bent to provide the downwardly and inwardly inclined spring member 17 for engaging 70 the side wall 10 of the type block 4, and the support for the type is further bent with the downwardly extending spring member 18 for engaging the side wall 11 of the type block 4, the lower edge of the spring 75 member 18 being inwardly bent to provide the gripping end 19 for engaging the undercut portion 12 of the type block 4. Upon the under side of the base 14 of the type support is formed the lug 20 for engaging 80 the recess 13 in the face of the type block 4.

In Figs. 4 and 5, 21 denotes the type bar provided with the recess 22 formed at a point slightly remote from the end of the bar. Mounted upon the end of the bar 21 85 is the type block 23 having formed upon its face the type 24 and 25, which type may be the usual small letters and capital letters. The type block 23 is provided with the shank 26, upon the lower end of which is 90 provided the elongated ferrule or sleeve 27. The ferrule or sleeve 27 is disposed transversely or right angularly to the shank 26, and has its closed end 28 projecting slightly beyond one side of the shank 26, while the 95 open end 29 of the sleeve 27 extends for a greater distance beyond the other side of the shank 26, the sleeve 27 being provided with the lug 30, adjacent its open end 29, for engaging the recess 22 of the type bar 21.

In the type bar shown in Figs. 1, 2, and 3, the base plate or support 14 may be a plate having one character of type thereon, and should it be desired to substitute this plate with another having a different character 105 of type, the first plate may be readily removed by gripping the type supporting plate with the fingers, or a suitable tool, and forcing the same lengthwise of the type block 4. This movement will cause the lug 110

20 of the plate 14 to become disengaged from within the recess 13 of the type block 4, and at the same time will overcome the impinging action of the spring members 17 and 18 5 of the plate 14 against the side walls 10 and 11 of the type block 4, thereby removing the type and its support from the type block 4. Subsequently the similarly constructed type plate may be substituted for the first plate 10 by forcing the same upon the block 4, the spring members of the second type plate impinging the side walls 10 and 11 of the block 4, and the lug upon the second plate 15 engaging the aperture 13 for locking the second plate upon the type block 4, the second type plate having upon its face, of course, type of a different character.

By forming the side wall 10 of the block 4 and the spring member 17 of the type 20 plate 14 of one shape, and the side wall 11 of the block 4 and the spring member 11 of the type plate 14 of another shape, provides an efficient means for preventing the substituted type plate from being wrongly positioned upon the type block 4. If it is not desired to change the character of the type, this arrangement is equally efficient, of course, for substituting another plate of similar type for the one previously used, 30 should the type on this latter plate become damaged from any cause or worn out, thus reducing the cost of repairs.

In the type bar shown in Figs. 4 and 5, the type may be readily substituted by other 35 type for either changing the character of the type when desired, or for replacing the type with other type when the first type has become damaged or injured in any way, by grasping the sleeve 27 with the fingers, or a 40 suitable tool, and forcing the sleeve outwardly, which movement will release the locking lug 30 from its engagement with the recess 22 of the type bar 21, whereby the present type block 23 with its type thereon 45 is removed, and a substituted type block introduced upon the end of the type bar 21.

While I have here shown and described the preferred embodiment of the invention, minor variations and alterations may be 50 made therein from time to time without departing from the spirit of the invention or the scope of the claims.

Having described my invention, what I

claim as new and desire to secure by Letters-Patent, is:—

1. In a device of the class described, the combination with a type bar, of means to provide for the interchanging of the type upon the bar, means to render impossible the positioning of the type in inverse order upon 60 the type bar at any stage, and means for locking said type upon said bar, said locking means comprising a recess and a lug for locking engagement with the recess.

2. In a device of the class described, the 65 combination with a type bar, of a type block secured upon said type bar, said type block having a flat face and its side walls disposed at different angular relations to its face, a type plate having depending resilient members of the contour of the side walls of said block for embracing the same, and means for detachably securing said type plate upon 70 said type block.

3. In a device of the class described, the 75 combination with a type bar, of a type block secured upon said bar, said type block having a flat face provided with a centrally disposed recess therein, one of the side walls of said type block being acutely undercut, the 80 other of the side walls of the type block being disposed in right angular relation to the face of said block but having its lower portion acutely undercut, a type plate for said type block having a centrally disposed lug 85 adapted to seat in the recess of said type block for detachably securing said type plate upon said type block, said type plate having depending resilient side members, one of which is formed to snugly engage the acutely 90 undercut side wall of said type block, the other formed to snugly engage the right angularly disposed side wall of said type block and having its lower edge inwardly bent for engaging the lower undercut portion 95 of said side wall, whereby to render impossible the positioning of said type plate upon said type block at any stage with the type in inverse order.

In testimony whereof I have signed my 100 name to this specification in the presence of two subscribing witnesses.

OLIVER PERRY ANDERSON.
